STOOL

Alexander L. Janes, Jr., St. Paul, Minn.

Application November 26, 1947, Serial No. 788,208

9 Claims. (Cl. 155—1)

1

My invention relates to improvements in stools for use by persons engaged in occupations requiring occasional reaching with his hands of places beyond his normal reach from any given sitting position. To this end, I provide an improved stool having its seat mounted on the base structure of the stool with freedom for upward and downward movements, and further incorporating a foot rest movably mounted on the supporting base structure of the stool and having operating connections to the upwardly and downwardly movable seat, whereby when the occupant of the stool transfers part of his weight from the stool seat to the foot rest thereof, the resultant force exerted on the foot rest will be transferred to the seat in a direction tending to raise the same.

Preferably, and in the embodiments of the invention herein illustrated, means, in the nature of a spring or springs is provided for yieldingly biasing the upwardly and downwardly movable seat of the stool in an upward direction, so as to greatly reduce the amount of pressure necessarily applied by the occupant to the foot rest or treadle of the stool in order to raise the torso of the occupant. In practice, I preferably provide a sufficiently-resilient upwardly-biasing force on the seat to largely, but not entirely, carry the weight of the occupant of the seat, so that when the occupant's full or major weight is applied to the seat, the seat will recede to a lower extreme stop position, representing the normal position of the seat, but from which the seat and the occupant's torso can be elevated, at will, by exertion on the foot rest of the stool of a comparatively light pressure exerted through the operator's feet. Hence, with this improved stool, the occupant can proceed to do such work as is within the normal reach of his arms while firmly supported in a desired plane by the stool, but whenever he desires to extend his reach by elevation of his torso and arms, he may do so by merely transferring a relatively small part of his total weight from the seat of the stool to the foot rest or treadle thereof.

There are numerous occupations or work tasks in which the workers or operators can advantageously use stools of the present invention, a few of these being as follows:

(a) A telephone operator working at a large vertical switchboard cannot usually reach all of the switches from a fixed sitting position, such as is afforded by a conventional stool, and must, therefore, when using a conventional stool, stretch excessively at times and at other times

2

rise from the seat of the stool in order to reach the extremities of the switchboard. Of course, this excessive stretching and periodical transfer of the operator's weight from the stool to his or her legs and feet is essentially tiring, and, to a large extent, defeats the purpose for which the seat was intended. However, when my improved stool is similarly employed by a telephone operator, the above noted objection to conventional stools is largely overcome, since the operator can readily elevate all portions of his body lying above the stool seat to correspondingly extend his reach by shifting a comparatively small portion of his total weight from the stool seat to his feet and legs. This, of course, greatly conserves the operator's energy and delays the point at which fatigue and inefficiency sets in.

(b) A draftsman using a conventional stool while working on a large drawing often finds it necessary to rise off of the stool seat in order to work on the far extremities of the drawing. However, when such a draftsman uses my improved stool, he can readily extend his reach without getting off of the seat of the stool, and by merely shifting part of his weight, preferably a relatively small part, from the seat of the stool to his feet and legs.

(c) Barbers are often able to use conventional stools for short periods, but find it necessary to rise from conventional stools periodically during each haircut which, of course, to a great extent defeats the purpose of the stool. However, barbers find that they can successfully use stools made in accordance with the present invention throughout most or all of a haircutting operation for the reason that they can elevate their positions and extend their reach and viewpoint at will and with exertion of a minimum of energy.

(d) Housewives ironing clothes also find the improved stools hereof to be very useful and for reasons more specifically pointed out above in connection with other occupations, and the same can be said for persons engaged in the sorting of various objects.

In view of the above, an obvious object of the invention is the provision of an improved stool, the occupant of which can elevate all that portion of his body lying above the seat to a desired extent, within certain limits, to thereby extend his reach or change his viewpoint, without rising off of the stool and by transferring from the stool seat to his legs and feet only a relatively small portion of his total weight.

A still further object of my invention is the provision of means for varying the extent of

movement of the seat relative to the base structure, and independent means for varying the biasing force of the above-mentioned resilient means.

Still another object of my invention is the provision of guard means between the seat and the base structure of the stool to prevent accidental pinching therebetween of the occupant's hands or fingers.

Still another object of my invention is the provision of a stool as set forth which is inexpensive to manufacture, rugged in construction, and efficient and durable in use.

Still further objects and advantages will become apparent from the following specification, appended claims, and attached drawings.

Referring to the drawings, in which like characters indicate like parts throughout the several views:

Fig. 1 is a perspective view illustrating a preferred embodiment of my invention;

Fig. 2 is a view in side elevation, some parts broken away and some parts shown in section, on a slightly enlarged scale;

Fig. 3 is an enlarged perspective view of an adjustable abutment means of my invention;

Fig. 4 is a fragmentary view, partly in plan and partly in section, taken substantially on the line 4—4 of Fig. 2;

Fig. 5 is a view corresponding to Fig. 2 but illustrating a modified form of my invention; and

Fig. 6 is an enlarged horizontal section taken substantially on the line 6—6 of Fig. 5, with some parts broken away.

Referring in greater detail to the embodiment of the invention illustrated in Figs. 1 to 4, inclusive, the numeral 1 indicates in its entirety a base structure which may be of any suitable form, but, as shown, comprises a top plate 2 provided with a tubular guide element in the nature of a depending circumferential flange 3, and a plurality of circumferentially-spaced legs 4 secured at their upper ends by spot welding or the like to a depending circumferential flange 5, on the top plate 2. The legs 4 diverge in a downward direction to provide a relatively wide base of support and are tied together intermediate their ends by rigid brace members 6 and 7.

The flange 3 defines a vertically extending passage 8 in which is slidably mounted for limited rotary and generally upward and downward reciprocating movements a guide element in the nature of a seat post 9. A seat 10, preferably circular in form, is secured to the upper end of a seat post 9 and may be equipped with a back rest 11, which is mounted fast thereon for common movements therewith by means of supporting members or the like 11a. I also provide means for limiting the extent of rotation of the seat, which comprises a pin 12 rigidly secured to the seat 10 and extending downwardly through a segmental aperture 13 in the top plate 2, for a purpose which will hereinafter become apparent.

The lower end portion of the seat post 9 is longitudinally slidably movable in a tubular guide element 14, which is axially aligned with and spaced from the flange 3 and which is rigidly supported from the brace members 6 and 7 by respective spider elements 15 and 16. The lower end portion of the guide element 14 is internally threaded to receive the threaded portion 17 of an abutment in the nature of a bushing 18 having therein an axial passage 19. A push rod 20

projects loosely through the passage 19 and at its upper end is provided with a head 21 that engages the bottom of the seat post 9. A coil compression spring 22 is interposed between the head 21 and the abutment-forming bushing 18, within the tubular guide element 14. The abutment forming bushing 18, may, if desired, be provided with a graduated weight indicating scale 18a to facilitate the initial setting thereof. A pointer (not shown) may be secured to the base structure to aid in reading the scale 18a or, if desired, the scale may be read against the bottom of the tubular guide 14.

As will be observed by reference particularly to Fig. 2, the spring 22 biases the seat 10 in an upward direction. A stop pin 23 extends through one of a series of transverse holes 24 in the seat post 9 and limits upward movement thereof by engagement with the lower end of the flange 3.

The extent of upward movement of the seat 10 is determined by the location of the stop pin 23 on the seat post 9. Downward movement of the seat 10 is limited by engagement with the top plate 2 or by engagement of the stop pin 23 with the upper end of the tubular guide element 14, depending, of course, upon the location of the stop pin 23 relative to the seat 10.

A treadle 25 comprises a foot rest 26 mounted on one end of a pair of laterally spaced lever arms 27, which, at their intermediate portions are provided with aligned longitudinally extended slots 28. A shaft 29 extends through the slots 28 and is secured at each of its ends to one each of a pair of the legs 4 adjacent the bottom of the base structure 1. At their inner ends, the lever arms 27 are pivotally secured to the lower end of the push rod 20, as indicated at 30. The shaft 29 provides a fulcrum for the lever arms 27 which are capable of sliding movements transversely of the shaft 29 as well as pivotal movements thereon. The sliding movements of the arms 27 are limited by the length of the slots therein and prevent binding of the push rod 20 within the tubular abutment bushing 18 during pivotal movements of the lever arm 27 and a consequent reciprocating movement of the push rod 20. It will be noted that the foot rest 26 is on a side of the base structure substantially diametrically opposite the back rest 11. The rotary movement of the seat 10 is limited to such an extent, and the length of the foot rest 26 is such, that the feet of an occupant of the seat 10 are at all times permitted to rest comfortably on foot rest 26.

As a safety measure, I provide a guard in the nature of a flange or apron 31, which is rigidly secured to and extends about the periphery of the seat 10. The apron 31 projects downwardly to a point where it encompasses the top plate 2, and is of such a size as to easily pass by the flange 5 of the top plate 2. The apron 31 is preferably made from sheet metal or other rigid material and prevents the occupant from getting his hands or fingers caught and pinched between the underside of the seat 10 and the top plate 2.

In use, the pin 12 is inserted into one of the holes 24 to give the desired maximum height to the seat 10. The effective pressure of the spring 22 against the end of the seat post 9 is then adjusted by moving the bushing 18 into a point where the spring pressure is slightly overbalanced by the weight of an occupant of the seat when the occupant's feet are resting on the treadle 25. The seat 10, under pressure of the occupant's weight, will assume the position in-

dicated by dotted lines in Fig. 2. Then when the occupant of the seat 10 exerts a very light downward pressure on the foot rest 26, a part of the weight of the occupant is naturally transferred from the seat 10 to the treadle 25. Downward movement of the foot rest 26 results in upward movement of the push rod 20 and the seat 10, aided by the upward biasing force of the spring 22. Thus the occupant is automatically raised to the desired height with a minimum of effort and is enabled to reach remote corners very easily as, for example, when ironing clothes, or when sorting postal items and the like. The combined treadle and spring action enables the occupant to raise and lower himself a great many times without experiencing the fatigue which results from repeated sitting and rising even when a stool having a conventional spring-mounted seat is used.

In the modified form of my invention illustrated in Figs. 4 and 5, I provide a base structure 1' comprising a top plate 2' and supporting legs 4'. The top plate 2' is provided with a flange 3' forming a tubular guide passage 8'. The legs 4' are connected intermediate their ends by brace members 6', which support a guide element 32 axially aligned with the passage 8'. A guide element in the nature of a seat post 9' extends through the passage 8' and the guide element 32, and at its upper end is secured to a seat 10' having a back rest 11'. A plurality of coil springs 33 are secured at their upper ends to an annular flange 34 fast on the underside of the top plate 2' and at their lower ends to an upwardly opening cup-shaped member 35. The member 35 is provided at its center with a depending circumferential flange 36 which defines an opening 37 loosely encompassing the seat post 9'. The springs 33 exert a biasing force on the member 35 toward an adjustment nut 38 which has threaded engagement with a threaded portion 39 of the seat post 9'.

A treadle 25' is identical to the treadle 25 and is carried by the base structure 1' in the same manner. The inner ends of laterally spaced lever arms 27' are pivotally connected to the extreme lower end of the seat post 9', as indicated at 30'.

Operation of the invention shown in Figs. 5 and 6 is identical to that of the preferred form of Figs. 1 to 4, inclusive.

My invention has been thoroughly tested and found to be entirely adequate for accomplishment of the objects set forth; and while I have disclosed a preferred embodiment and a modified form of my device, it will be understood that the same is capable of still further modification without departure from the spirit and scope of the invention as defined in the following claims.

What I claim is:

1. In a stool of the class described, a base structure, a seat overlying said base structure, cooperating guide elements on said seat and said base structure guiding the seat for upward and downward reciprocating movements with respect to said base structure, adjustable means on one of said guide elements for variably limiting the extent of movement of said seat in one direction, yielding means biasing the seat in an upward direction, a treadle located adjacent the bottom of said base structure and adapted to be engaged by the feet of an occupant of said seat, means mounting said treadle on the base structure for generally upward and downward reciprocating movements with respect thereto, and connections

on said seat and said treadle cooperating with said yielding means for imparting movements to said seat in one direction responsive to pressure exerted by the occupant on said treadle in the opposite direction.

2. In a stool of the class described, a base structure, a seat overlying said base structure, a generally vertically extending tubular guide element in said base structure, a seat post on said seat longitudinally slidably mounted in said guide element, adjustable means on said seat post for limiting the extent of longitudinal movement thereof in said guide element, a treadle located adjacent the bottom of said base structure and adapted to be engaged by the feet of an occupant of said seat, means mounting said treadle on said base structure for generally upward and downward reciprocating movements with respect thereto, and operating connections between said treadle and said seat post for imparting movements to said seat in one direction responsive to pressure exerted by the occupant on said treadle in the opposite direction.

3. In a stool of the class described, a base structure, a seat overlying said base structure, a generally vertically extending tubular guide element in said base structure, a seat post on said seat longitudinally slidably mounted in said guide element, an abutment longitudinally adjustably mounted in said guide element, a compression spring in said guide element between said abutment and said seat post whereby to bias said seat in an upward direction, a treadle located adjacent the bottom of said base structure and adapted to be engaged by the feet of an occupant of said seat, means mounting said treadle on said base structure for generally upward and downward reciprocating movements with respect thereto, and a push rod extending slidably through said abutment and operatively associated with said treadle and said seat post, said treadle and push rod cooperating with said spring to impart movement to said seat in one direction.

4. In a stool of the class described, a base structure, a seat overlying said base structure, a generally vertically extending tubular guide element in said base structure, a seat post on said seat mounted in said guide element for reciprocating and arcuate movements with respect thereto, an abutment longitudinally adjustably mounted in said guide element, a compression spring in said guide element between said abutment and said seat post whereby to bias said seat in an upward direction, a treadle located adjacent the bottom of said base structure and adapted to be engaged by the feet of an occupant of said seat, means mounting said treadle on said base structure for generally upward and downward reciprocating movements with respect thereto, and a push rod extending slidably through said abutment and operatively associated with said treadle and said seat post, said treadle and push rod cooperating with said spring to impart movement to said seat in one direction.

5. In a stool of the class described, a base structure, a seat overlying said base structure, a guide element in said base structure, a seat post on said seat and mounted in said guide element for reciprocating movements with respect thereto, a tension spring extending generally longitudinally of said seat post and having its opposite ends connected to the upper portion of said base structure and the lower portion of said seat post, said spring biasing said seat in an upward direction, a treadle located adjacent the bottom of

said base structure and adapted to be engaged by the feet of an occupant of said seat, and means mounting said treadle on said base structure for generally upward and downward reciprocating movements with respect thereto, said treadle being connected to said seat post and cooperating with said spring to impart movement to said seat in one direction.

6. The structure defined in claim 3 in further combination with means limiting reciprocating movement of said seat post in one direction.

7. The structure defined in claim 3 in further combination with means for adjusting the biasing force of said spring.

8. In a stool of the class described, a base structure, a seat overlying the base structure and mounted and guided therein for generally upward and downward movements, a treadle located below the plane of the top of the seat and having a foot-engaged portion, means mounting the treadle on the base structure for upward and downward movements of its foot-engaged portion, operating connections between the treadle and seat for transmitting upward lifting force on the seat responsive to downward movements of the foot-engaged portion of the treadle, the foot-engaged portion of the treadle throughout its entire range of movement being located sufficiently close to the plane of the marginal edge of the seat and sufficiently below the plane of the top of the seat that it may be normally downwardly engaged by the feet of a seat occupant throughout the entire ranges of movement of the treadle and the seat, thereby allowing a seat occupant to transfer varying proportions of his body weight from the seat to the treadle in all positions of the seat and treadle.

9. In a stool of the class described, a base structure, a seat overlying the base structure and mounted and guided therein for generally upward and downward movements, yielding means exert-

ing an upward lifting force on the seat, a treadle located below the plane of the top of the seat and having a foot-engaged portion, means mounting the treadle on the base structure for upward and downward movements of its foot-engaged portion, relatively rigid operating connections between the treadle and seat and transmitting upward lifting force on the seat responsive to downward movements of the foot-engaged portion of the treadle, the foot-engaged portion of the treadle throughout its entire range of movement being located sufficiently close to the plane of the marginal edge of the seat and sufficiently below the plane of the top of the seat that it may be normally downwardly engaged by the feet of a seat occupant throughout the entire ranges of movement of the treadle and the seat, thereby allowing a seat occupant to transfer varying proportions of his body weight from the seat to the treadle in all positions of the seat and treadle, lifting force exerted on the seat through the treadle being independent of and additive to that exerted on the seat by the yielding means.
